UNITED STATES PATENT OFFICE

JOHN O. WINKS, OF SAN FRANCISCO, AND EDWARD O. BENNETT, OF GILROY, CALIFORNIA, ASSIGNEES TO BRADLEY L. BENSON, OF SAN FRANCISCO, CALIFORNIA.

LOCK.

Application filed April 2, 1921. Serial No. 458,118.

To all whom it may concern:

Be it known that JOHN O. WINKS, a citizen of the United States of America, residing at 1014 Balboa Building, in the city and county of San Francisco and State of California, and EDWARD O. BENNETT, a citizen of the United States of America, residing at the city of Gilroy, in the county of Santa Clara and State of California, have invented certain new and useful Improvements in Locks, of which the following is a specification.

The present invention is an improved lock.

The primary object of the invention is to provide a lock which is cylindrical in form throughout the structure to adapt it for use, as on doors, without necessitating a rectangular mortise.

A secondary object is to provide a lock, the component parts of which are interlocking in such a manner that the lock may be installed, as on a door, without the use of screws or other fastening means.

In the device hereinafter described it will be seen that the lock may be assembled in a door and that no dismemberment is possible save from the edge of the door when in locked position.

In office buildings, for instance, much expense is incurred in installing the usual type of lock and the services of skilled workmen are required to hang and install it.

It is obvious that a lock which can be installed in a bore made with a bit or boring tool will effect a considerable saving.

Another object which we seek to attain is to provide lock structure wherein all the parts are designed to be formed by punch press, and screw machine operation and requiring a minimum amount of assembling or hand labor at the factory.

Other objects and structural advantages will appear as the description proceeds.

In this specification and the annexed drawings, the invention is illustrated in the form considered to be the best, but it is to be understood that the invention is not limited to such form, because it may be embodied in other forms and it is also to be understood that in and by claims following

the description it is desired to cover the invention in whatever form it may be embodied.

In the accompanying three sheets of drawings, Fig. 1 is a fragmentary edge elevation of a typical office door showing cylindrical bores therein adapted to enclose and engage the bolts and parts of our lock. 55

Fig. 2 is a side elevation of Fig. 1 and 60 showing intersecting counter bores for enclosing and engaging the knob spindle housing and the lock cylinder.

Fig. 3 is an end elevation of our lock 65 assembled but without the knobs and spindle, the view corresponding to Fig. 1, which is indicated in dotted lines showing the relative position of the parts to Fig. 1.

Fig. 4 is a side elevation of Fig. 3, the dotted lines indicating the relative position 70 of the parts to Fig. 2.

Fig. 5 is a top plan view of Fig. 3.

Fig. 6 is a bottom plan view of Fig. 3.

Figs. 7 and 8 and 9 are side elevations 75 of three parts of a composite knob spindle housing.

Fig. 10 is a section of Fig. 7 on the line X—X.

Fig. 11 is a section of Fig. 9 on the line XI—XI. 80

Fig. 12 is a perspective view of a cylindrical bolt housing showing bayonet slots for engagement with the member shown in Fig. 8.

Fig. 13 is a central section of the part 85 shown in Fig. 12.

Fig. 14 is an end view of Fig. 8.

Fig. 15 is an assembly view of the spring bolt mechanism adapted to be housed by the member shown in Figs. 12 and 13. 90

Fig. 16 is a central section of the parts shown in Fig. 15.

Fig. 17 is an elevation of the spring bolt and link for throwing same.

Fig. 18 is a side elevation of Fig. 17. 95

Fig. 19 is an end view of a cylindrical housing for a dead bolt.

Fig. 20 is a side elevation of Fig. 19.

Fig. 21 is an end elevation of Fig. 20 showing the end opposite that shown in 100 Fig. 19.

Fig. 22 is a side elevation of a slotted

and counter bored plug member adapted to slide into the member shown in Fig. 20.

Fig. 23 is a section of Fig. 22 taken on the line XXIII—XXIII.

5 Fig. 24 is an end view of a clip member adapted to lie in a groove in the plug shown in Figs. 22 and 23.

Fig. 25 is a side elevation of Fig. 24.

10 Fig. 26 is an edge elevation showing two escutcheon plates and the means for interlocking same with the member shown in Figs. 22 and 23.

15 Fig. 27 is a side elevation of Fig. 26 and indicating in dotted lines the relative positions of the escutcheon plates when inserted in a door and before the interlocking means becomes effective.

20 Fig. 28 is a view similar to Fig. 26 showing the interlocking means of one of the escutcheon plates.

Fig. 29 is a bottom plan view of Fig. 28.

Fig. 30 is a side elevation of a dead bolt.

Fig. 31 is a bottom plan view of Fig. 30.

25 Fig. 32 is a side elevation of a knob spindle showing a crank thereon.

Fig. 33 is an end elevation of Fig. 32.

Fig. 34 is a side elevation of a key constructed for use with our lock.

30 Fig. 35 is a side elevation of a spool adapted to receive the key and be rotatably held in a cylinder on an escutcheon plate.

Fig. 36 is a bottom plan view of Fig. 35.

Fig. 37 is an end elevation of Fig. 35.

Fig. 38 is an end elevation of Fig. 36.

35 Fig. 39 is a view of the end of Fig. 35 opposite that shown in Fig. 37.

Referring to the drawings; Figs. 1 and 2, the letters A and B indicate respectively cylindrical bores in the edge of a door indicated fragmentally at 1, and adapted to receive and contain respectively a spring bolt housing 2, and a dead bolt housing 3.

40 As shown in Fig. 2, counter bores C and D intersect respectively the bores A and B.

45 The counter bore C is for the purpose of engaging the knob spindle housing and the parts therein which coact to operate a latch or spring bolt 4.

50 The counter bore D is adapted to admit and retain a lock cylinder housing 7 containing parts adapted to throw a dead bolt 8.

55 While it is obvious that either the spring bolt or the dead bolt might be used alone without departing from the spirit of our invention, we elect to show them together in order to accomplish all the operations necessary on a typical door lock.

60 If the spring bolt were used alone the escutcheon plates might be circular and relatively very small.

As both the spring bolt and dead bolt mechanisms are assembled and inserted as units we will describe both in detail and then show their relation to the other parts.

65 The dead bolt 8, Figs. 30, 31, has a reduced flat portion 9 provided with a shoulder 11 adapted to limit the throw of the bolt 4 by engaging parts to be described later.

A lug 12 acts as a stop to limit the throw of the bolt in the opposite direction, by 70 engaging the end of a slot 13 in the dead bolt housing, Figs. 20, 21, through which said lug extends when the parts are assembled.

The bolt 4 is provided with a reduced 75 stem member 14, Figs. 17 and 18, which is bifurcated at the end remote from the bolt. A pin 16 extends through the bifurcation to form a pivot for a link 17 adapted to be engaged and reciprocated by a crank 18 80 in a knob spindle 19, Figs. 32, 33.

The spindle 19 is preferably formed of rod material and is flattened as indicated at 21. The ends of the spindle are provided with the usual threaded holes 22 for 85 engaging a screw to hold a knob indicated in dotted lines at 23, Fig. 4.

The reduced portion 14, Fig. 6, is surrounded by a coiled spring 24 adapted to bear at one end against the head of bolt 90 4 and at the opposite end against a washer surrounding stem 14.

The parts are held in operative position in a cylindrical shell 27 by ears 28 and 29, Fig. 16, bent inwardly to form stops for 95 the spring pressed washer 26. A washer 31 bears against the ears 28 and 29 on the side remote from washer 26.

When the spring bolt mechanism described is assembled as shown in Fig. 15, it is slid 100 into the housing 2, Fig. 13, from above, and is prevented from being drawn through said housing by an annular flange 32, Fig. 13. The spring bolt mechanism is now ready for interlocking engagement as a unit with other parts to be described. The housing 2 is provided with bayonet slots 33 the purpose of which will be later disclosed.

We will now describe the dead bolt mechanism. 110

The reduced portion 9 of bolt 8, Figs. 30, 31, is provided with grooves 34 formed by a milling cut. The purpose of these grooves, one of which is on either side of the member 9, is to engage with an extended leg 36 of the 115 bifurcated end of a key 37, Fig. 34. This groove structure permits the throw of the bolt by a key inserted from either side of the bolt and yet positively prevents any person from poking the key out of the lock from 120 the opposite side.

While a slot extending clear through the metal would accomplish the desired result (allow the bolt to be actuated when a key is inserted from either side), we prefer to 125 leave a web portion 38, Fig. 31, as it serves to obstruct vision through the key-hole.

The head of the dead bolt 8 slides in a

plug 39, Figs. 19 and 20. The reduced portion 9 has a sliding bearing in a slot 41, in a removable plug member 42, Figs. 22 and 23.

To provide a definite length of throw for the bolt 8 and give an audible click at each end of the stroke, we provide a ball, 20, Fig. 30, which is pressed upwardly by a spring 25 to engage depressions 30 in the plug 39, Figs. 19 and 20.

This member 42 is adapted to slide freely into one end of a dead bolt housing 3, Fig. 20, and is provided with a counter-bore 43 adapted, when these parts are assembled, to register with similar openings 44 in the housing 3. The bores 43 and 44 are of a size calculated to admit lock cylinders 7 on escutcheon plates 47, Fig. 26.

The lock cylinders 7, Figs. 26 and 28, are provided with bayonet slots 48, Fig. 29. The larger or entrant parts of these slots are of a width sufficient to clear upturned ears 49, 51, of a U-shaped clip 52, Figs. 24, 25. This clip is adapted to lie in a groove 53 in the plug 42, Fig. 22. While this groove entirely surrounds the plug the upper portion has no function, merely representing a lathe tool cut.

When the clip 52 is placed in the groove 53 and the plug 42 inserted in the housing 3, and the bores 43 and 44 are in register, the lock cylinders 46 may be inserted from either side as shown in Fig. 26. By rotating the escutcheon plates 47 to the dotted line positions, shown in Fig. 27, the entrance portions of the bayonet slots 48 clear the upstanding ears 49 and 51, and if the escutcheon plate or plates be turned to the vertical position, shown in full lines in Fig. 27, the ears 49 and 51 enter the bayonet slots and the escutcheon plates are secured from lateral displacement or withdrawal.

Rotation of the escutcheon plates is prevented by a composite knob spindle housing, shown in Figs. 7, 8 and 9, which, when interlocked, extend through holes 52 in the escutcheon plates.

The central member 53, Fig. 8, of the composite housing is cut away, as shown at 54, and two tongues 56 and 57 extend into the cut from opposite directions.

Two ears 58 and 59 are turned inwardly from the cylindrical wall of the housing member 53.

The members 61, Fig. 7, and 62, Fig. 9, are adapted to slide within the member 53 from opposite ends and each is provided with a bayonet slot 63, the larger entrance portion of which will clear the inwardly bent ears 58 and 59 as the case may be and the slot portion when the members are turned engages said ears against withdrawal.

In order to lock the spring bolt housing and the composite spindle housing in a solid

65 T or cross-head position, we insert the spring

bolt casing 2 with the bolt and actuating means contained therein in the cut away portion 54 of member 53, Fig. 8.

The parts being cylindrical, it will be seen that when the end edge surfaces (indicated at 64) encounter the marginal wall of the cut 54 (indicated at 66), the bayonet slots 63 are on a plane to engage the tongues 56 and 57 if the housing 2 be rotated.

When so rotated the edge of the housing 2 extends into the member 53 and the entrant portions of the bayonet slots 63, Figs. 7 and 9, engaging said slots securely against rotation.

It will be seen that when assembled in 80 this cross-head form the parts can only be disassembled by rotating the casing 2 from the edge of the door.

We provide notches 67, Fig. 13, diametrically opposed in the external end of the 85 spring bolt casing 2. By this means the parts may be locked or unlocked by the use of a suitable key or spanner from the edge of the door.

We provide spool members 71, Figs. 33, 36, to engage the key 37 and rotate therewith. These spools are carried in the housing 7 in the escutcheons 47.

A pin 72 extends through a slot in each of the cylinders 7 to hold the spool in, and the rotation of the spool is limited by the length of the slot.

The central shank portion of the spools allow for suitable wards 73, to register with notches 74 in the key 37 in a well known 100 manner.

The spool is nearly split through its axis; a web 74 engages the bifurcated end of the key.

Operation.

105

Our lock is assembled in a door in the following manner:

The dead bolt housing 3, with the bolt and plug 43, Fig. 22, therein, is inserted in the bore B until the bores 43 and 44, Figs. 20 and 22, register with the counter bore D. One escutcheon plate is applied to either side of the door in the dotted positions shown in Fig. 27, and securely locked by turning the escutcheon to a vertical position, at which time the hole 52 registers with the counter-bore C.

The member 53, Fig. 8, is now inserted in the counter-bore C and the other escutcheon applied as before, members 61 and 62 are now inserted until the ferrules 68, Fig. 9, encounter the escutcheon plates. The members 61 and 62 are rotated until they become locked by the engagement of bayonet 125 slots 63 with ears 58 and 59.

The spring bolt housing is now inserted with the bolt actuating means contained therein and rotated until the bayonet slots 63, Fig. 12, engage tongues 56 and 57.

130

The device is now securely locked against dismemberment by the application of extraneous force and cannot be disassembled without the use of a special tool used when the door is open.

We claim:

1. A lock, comprising, in combination, two cylindrical members adapted to enter two parallel cylindrical mortises laterally of a door, an escutcheon connecting said members, and attached to one of them and engaged by the other when in normal position, members adapted to enter cylindrical mortises in the edge of a door and engage and lock said first named members, said attached member being locked by the swing of the escutcheon from non-normal to normal position, said escutcheon being locked by the engagement therewith of said non-attached member.
2. A lock, comprising, in combination, a cylindrical member adapted to extend crosswise of a door, an escutcheon at the end thereof, and a cylindrical member adapted to engage said escutcheon and enter said first named cylindrical member and lock therein.
3. A lock, comprising, in combination, a cylindrical member adapted to extend crosswise of a door, an escutcheon at each end thereof, said escutcheons being perforated in register with said cylindrical member, flanged cylindrical members adapted to extend through the perforations in said escutcheons and enter said first named cylindrical member and locking means therein adapted to engage the same.
4. A lock, comprising, in combination, an escutcheon, a cylindrical member attached thereto and adapted to extend crosswise of a door to which the escutcheon may be applied, a cylindrical member adapted to extend parallel to said escutcheon, said attached member having bayonet slots in its end and said last named cylindrical member having, adjacent to its end, a complementary configuration adapted to engage said bayonet slots and lock said members together.
5. A lock, comprising, in combination, a cylindrical member adapted to house a bolt and to enter the edge of a door, an escutcheon and a cylindrical member attached thereto, said two cylindrical members hav-

ing complementary elements adapted to engage and lock by the rotation of said attached member, said last named member being so attached to said escutcheon as to lock with said bolt-housing member by the swinging of said escutcheon from a non-normal to its normal position.

6. A lock, comprising, in combination, two cylindrical bolt-housing members adapted to occupy parallel positions, two escutcheons each provided with a cylindrical housing member projecting toward one of said bolt-housings, said members having complementary configurations adapted to engage and lock by the swing of the escutcheon from a non-normal to normal position, and a composite cylindrical member composed of three sections, adapted to extend between said escutcheons, the end sections adapted to engage and lock the escutcheons in their normal positions, and to be engaged and locked the central section.

7. In a door lock, a composite knob spindle housing comprising a central member adapted to be contained within the door and provided with openings in both ends and with an opening in the side thereof, ferrule members adapted to engage with the ends of said central member, and complementary configurations on all of said members arranged to interlock the parts, and a bolt housing adapted to engage the said central member in the side opening, and means on said bolt housing for engaging the complementary interlocking portions to prevent dismemberment except by removal of the bolt housing.

8. In a door lock, a bolt housing, a plug at one end thereof, said plug having a longitudinal opening to receive the bolt, a plug at the opposite end of said housing perforated laterally to receive the bolt operating means and grooved circumferentially, a U-shaped clip adapted to rest in said groove and have its ends project into the lateral perforation, and ferrule members having bayonet joints adapted to engage said projecting ends and be locked thereby.

In testimony whereof we affix our signatures.

JOHN O. WINKS.
EDWARD O. BENNETT.
